UNITED STATES PATENT OFFICE.

FRITZ SALATHE, JOHN E. BRUSTLEIN, AND PAUL SURY, OF NEW YORK, N. Y.

ELECTRIC LAMP.

SPECIFICATION forming part of Letters Patent No. 242,081, dated May 24, 1881.

Application filed March 5, 1880. (No model.)

To all whom it may concern:

Be it known that we, FRITZ SALATHÉ, JOHN E. BRUSTLEIN, and PAUL SURY, all of the city of New York, in the county and State of New York, have invented certain new and useful Improvements in Electric Lights, of which the following is a specification.

One of our improvements consists in the combination, in an electric light, of a transparent shell or globe, two metallic-rod conductors arranged in said shell or globe, a carbon ring forming the incandescent or light-giving portion of the electric circuit, and carbon clamps holding the carbon ring between them, and secured upon the metallic-rod conductors by means of screw-nuts, whereby the said rod-conductors are prevented from being unduly heated by the great heat of the incandescent ring.

Another of our improvements consists in the combination, in an electric light, of a closed transparent shell or globe, a carbon or other light-giving device arranged therein, and two vases or vessels, one containing a chemical or chemicals for absorbing oxygen, and the other a substance for absorbing nitrogen, placed one within the other, and arranged in the shell or globe. One or both of the vases or vessels which contain the chemical or chemicals may be silvered upon its exterior or otherwise prepared so as to form a reflecting-surface for reflecting rays of light outward.

In the accompanying drawings, Figure 1 represents a central vertical section of an electric lamp embodying our improvements; and Fig. 2 represents a horizontal section thereof upon the dotted line $x-x$, Fig. 1.

Similar letters of reference designate corresponding parts in both the figures.

A designates the shell or globe for containing the light-giving devices, and which may be of any desirable size. As here represented, its upper end, A', is convex internally, so that it forms a reflector for reflecting the rays of light downward and outward, as illustrated by the broken lines in Fig. 1. The reflecting-power of this lenticular portion may be greatly increased by silvering or otherwise preparing its inner surface.

B designates two metallic rods which are

supported in and extend through the stopper of the shell or globe, and support at or near their inner ends the carbon or other light-giving device or devices. These rods also constitute the conductors through which the electric current is passed, the positive conductor of a battery or electric machine being connected to one rod, and the negative conductor to the other rod.

C designates the carbon or light-giving device, here represented as in the form of a carbon ring, adapted to be heated to a point of incandescence by the resistance offered to the passage of the electric current through it. The said ring is supported by means of clamps a, of carbon, holding the ring between them, and fitted upon the ends of the rod-conductors, to which they are secured by means of screw-nuts b fitted to the rod-conductors. This arrangement of carbon clamps for holding ring C prevents the rods B from being injured by the great heat of the ring, when heated to a point of incandescence.

D designates vases, vessels, or receptacles, of which two are here represented, one placed inside the other, and both arranged in the shell or globe A, which should be closed and sealed air-tight. These vases or vessels are for the purpose of containing a chemical or chemicals having the power of absorption. The vases or vessels, after being filled with the chemical or chemicals, are stopped by means of stoppers C, made of asbestos or other suitable material which is sufficiently porous to allow the air or gas contained in the shell or globe to reach the chemical or chemicals in the vases or vessels, but which will confine the chemicals during the time of the insertion of the said vases or vessels into the shell or globe. By employing different chemicals in these vessels or vases the atmospheric air contained in the shell or globe at the time of closing or sealing it is deprived of its oxygen by absorption, while a large percentage of the remaining nitrogen is also absorbed and a partial vacuum produced, which tends to preserve the carbon or other electrodes. A partial vacuum will be produced by the absorption of the oxygen, and this may be all that is desired in some cases; but in order to obtain a more nearly perfect vacuum,

we preferably also employ a vase or vessel containing a chemical for absorbing the remaining nitrogen. If at the time of sealing or closing the shell or globe we fill the vessel or vase inclosed therein with pyrogalate of potassium, sulphate of iron, chloride of iron, or metallic sodium, either of which is an absorbent of oxygen, a partial vacuum will be produced and maintained by the absorption of the 10 oxygen, leaving nitrogen-gas of a low tension. If a second vase or vessel be filled with freshly-burned charcoal and inclosed in the shell or globe, a large portion of the nitrogen will be absorbed and the vacuum made more nearly 15 perfect.

Various methods may be adapted for hermetically sealing the shell or globe after the introduction of the gas. In the present example of our invention we have represented a disk of 20 cork, E, which fits the shell or globe tightly, and has upon its face a disk of wood, F, in which the metallic-rod conductors are fixed. After inserting the cork stopper, asphaltum in a melted state or other suitable material may 25 be poured over the cork for sealing it, as represented at G, Fig. 1.

In order to increase the reflecting-surface of the lamp, one or both of the vases or vessels D may have a silvered surface.

We are aware that it is old to charge the shell 30 or globe of an electric lamp with nitrogen-gas and place therein a small piece of sodium or other chemical to absorb whatever oxygen may enter the shell or globe through leakage. Our 35 invention differs from this in that we employ a shell or globe filled first with atmospheric air, and a large amount of chemical is necessary to absorb the oxygen—so much, indeed, that it

could not be introduced without some special arrangement for its reception. The vases or vessels being arranged one within the other may be placed in the center of the shell or globe, and will not therefore interfere with the transmission of light.

What we claim as our invention, and desire 45 to secure by Letters Patent, is—

1. The combination, in an electric lamp, of a transparent shell or globe, two metallic rod-conductors arranged therein, a carbon ring forming the light-giving portion, and carbon clamps 50 holding the carbon ring between them fitting upon the metallic-rod conductors, and screws for tightening said clamps upon said rods, substantially as and for the purpose specified.

2. The combination, in an electric light, of a 55 closed transparent shell or globe, a carbon or other light-giving device arranged therein, and two vases or vessels, one containing a chemical or chemicals for absorbing oxygen and the other a substance for absorbing nitrogen, 60 placed one within the other and, arranged in the shell or globe substantially as specified.

3. The combination, in an electric lamp, of a closed transparent shell or globe, a carbon or other light-giving device arranged therein, and 65 a vase or vessel for holding a chemical, also arranged in said shell or globe, and having a silvered surface, whereby it is made to constitute a reflector, substantially as and for the purpose specified.
